CLAIM

The ornamental design for an animal waste receptacle, as shown and described.

DESCRIPTION

FIGS. 1 through 3 are perspective views of an animal waste receptacle showing our new design;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines, including stitching, shown in the drawings are for environmental purposes only and form no part of the claimed design.
